US00D579932S

(12) **United States Design Patent**
Huang

(10) **Patent No.:** **US D579,932 S**
(45) **Date of Patent:** **** Nov. 4, 2008**

(54) **PORTABLE ELECTRONIC DEVICE**

(75) Inventor: **Chien-Hsin Huang**, Taoyuan (TW)

(73) Assignee: **HTC Corporation**, Taoyuan (TW)

(**) Term: **14 Years**

(21) Appl. No.: **29/266,133**

(22) Filed: **Sep. 15, 2006**

(30) **Foreign Application Priority Data**

May 25, 2006 (TW) 95302847

(51) **LOC (8) Cl.** **14-02**

(52) **U.S. Cl.** **D14/346**

(57) **CLAIM**

The ornamental design for a portable electronic device, as shown and described.

DESCRIPTION

FIG. 1 is a perspective view of the front, bottom and right side of a portable electronic device showing my new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a rear elevational view thereof.

The portions of the portable electronic device shown in broken lines form no part of the claimed design.
